(57) CLAIM

The ornamental design for a cover, as shown and described.

DESCRIPTION

In a preferred embodiment, the nature of this product is a toilet bowl cover.

FIG. 1 is a left, top, front perspective view of a cover embodying my new design;

FIG. 2 is a top plan view thereof;

FIG. 3 is a left side elevational view thereof, the right side elevational view thereof being a mirror image of the left side shown;

FIG. 4 is a front elevational view thereof;

FIG. 5 is a rear elevational view thereof;

FIG. 6 is a bottom plan view thereof;

FIG. 7 is a left, top, front perspective view of a cover according to another embodiment of my new design;

FIG. 8 is a top plan view thereof;

FIG. 9 is a left side elevational view thereof, the right side elevational view thereof being a mirror image of the left side shown;

FIG. 10 is a front elevational view thereof;

FIG. 11 is a rear elevational view thereof; and,

FIG. 12 is a bottom plan view thereof.

The broken line representations of seat environment in FIGS. 1 and 7 are for the purpose of illustration only, and form no part of the claimed design.
